CLAIM

The ornamental design for a combined pager and magnetic key, as shown and described.

DESCRIPTION

FIG. 1 is a top plan view of a combined pager and magnetic key showing our new design;

FIG. 2 is a bottom plan view thereof;

FIG. 3 is a left side elevational view thereof;

FIG. 4 is a right side elevational view thereof;

FIG. 5 is a front elevational view thereof; and

FIG. 6 is a rear elevational view thereof.

FIG. 1.FIG. 2.FIG. 3. FIG. 4.FIG. 5.FIG. 6.
